UNITED STATES PATENT OFFICE

2,639,683

PORTABLE SEWING MACHINE

Harry W. Huntington, Cranston, R. I.

Application January 24, 1949, Serial No. 72,378

9 Claims. (Cl. 112—169)

1

My invention relates to improvements in portable sewing machines.

Sewing machines of the standard well known type, have usually been mounted on stands which take up a substantial amount of room, require a person to sit down to operate them, and due to their inherent mechanism, take up a substantial amount of space.

Due to the above facts and the fact that people, particularly in cities, are living under crowded conditions, the use of sewing machines, particularly in the city, has greatly decreased.

An object of my invention is to provide a sewing machine which can be used in every home even under the most crowded conditions, one which is self-contained, portable, light in weight, compact and readily manipulatable.

For this purpose, I provide a light, small housing of generally solid elliptical shape and having an elongated body for readily grasping in the palm of a hand, and a head having a narrow, transverse fabric receiving slot therein, containing the stitch forming means therein located above and below said slot, a thread supply in said housing suitably fed to said stitch forming means under tension, a small electric motor mounted in said housing, and suitable power transmitting means, including gear means operated by said electric motor for actuating the stitch forming means, said housing having a switch and cord means leading to a suitable source of electric supply such as a floor plug.

A further object of my invention, due to the fact that all operating parts are contained within a single, light housing, is to provide a sewing machine which will positively work in poor light, may be operated by people with poor eyesight or children, automatically, with positively no danger of injury to the operator.

A further object of my invention is to provide a sewing machine which is so light in weight that it may be readily grasped in the user's hand and used over long periods of time without fatigue to the user.

A further object of my invention, due to its particular construction of containing a complete spool of thread therein, is that it is always ready for use, needs no particular preparation to start, and will continue to give continuous stitches for the whole spool of thread, if necessary.

A further object of my invention, due to the use of a single unit spool already on the market as a source of thread supply, is that I eliminate the rewinding of any thread on bobbins or other devices formerly thought necessary in other types of sewing machines.

2

A further object of my invention is to provide a device which is so small and takes up so little room, that there is always room to store it even in the smallest city apartment, and which can readily have its operating cord wrapped around it and packed in a dress suitcase for traveling purposes, if desired.

A further object of my invention is to provide a device which, as it is completely portable, can be used to reach heretofore inaccessible places in the manufacture or repair of clothes and which can be readily operated by the user in a standing or sitting position without the use of a stand, chair or table, and which may even be used by the user to repair the clothes which she or another is wearing, and which may be readily manipulated by the user to achieve all types of results.

A further object of my invention is to provide a device which may be readily assembled and disassembled.

A further object of my invention is to provide a device which is relatively inexpensive to manufacture and which, therefore, is well within the price range of any user.

A further object of my invention is to provide a device which may be operated by any standard type of available current, such as 110 A. C. or 110 D. C. and which is of such a low horsepower that the cost of operating it is substantially negligible.

A further object of my invention relates to the safety switch preferably employed by me for positively preventing the operation of the motor until the head is completely closed and locked in operating position.

A further object of my invention relates to the improved structure of housing and the location of parts to provide a device which will function mechanically while occupying a minimum amount of space, and to be of light weight.

A further object of my invention relates to the inherent construction of the parts which include gearing for the transmission and application of power, a novel feature in sewing machines, providing a construction which will function with a minimum amount of friction, permitting the parts to last without replacement a substantially long period of time.

A further object of my invention relates to the fabric receiving slot, the height of which positively limits the thickness of material which may be inserted therein to positively prevent overloading of the small motor which might destroy the electrical properties of the motor and its electrical connections.

A further object of my invention relates to the provision of the positive needle return spring I preferably employ.

A further object of my invention relates to the specific construction of mechanisms employed covering modifications of well known sewing machine mechanisms, so as to permit their use within the small compass or space provided in the head of the housing, specifically with the needle reciprocating mechanism being gear operated instead of lever operated in a novel specific manner and with the stitch looping and fabric feeding mechanisms being conjointly operated through gearing in a novel manner, so that the fabric feeding mechanism, stitch looping mechanism and needle reciprocating mechanism will all function at the desired predetermined portions of successive stitch forming cycles.

These and such other objects of my invention as may hereinafter appear will be best understood from a description of an embodiment thereof, such as is shown in the accompanying drawings.

In the drawings,

Fig. 1 is a perspective view of my improved portable sewing machine showing it grasped by the hand in position actually sewing a hem on a garment.

Fig. 2 is a perspective view of my improved sewing machine per se with the upper head portion and spool compartment cover pivoted to open positions.

Fig. 3 is a detail sectional view of the thread tensioning mechanism.

Fig. 4 is a central longitudinal vertical sectional view through the housing showing my improved sewing mechanism.

Fig. 5 is a transverse sectional view taken along the line 5—5 of Fig. 4 through the motor.

Fig. 6 is a transverse sectional view taken along the line 6—6 of Fig. 4 through the spool compartment, switch and transmission gearing.

Fig. 7 is a transverse sectional view taken along the line 7—7 of Fig. 4 through the head portion thereof, showing the front end of the transmission gearing I preferably employ.

Fig. 8 is an enlarged sectional view through the front portion of the head taken along the line 8—8 of Fig. 4 and specifically illustrating the needle reciprocating mechanism, the thread looping mechanism and the fabric feeding mechanism.

Fig. 9 is a detail diagrammatic plan view of the transmission head gearing, showing adjacent portions of the housing in section.

Fig. 10 is an enlarged vertical sectional view taken through the head portion of my invention and showing the front wall of the body portion.

In the drawings, wherein like characters of reference generally indicate like parts throughout, 10 generally indicates a portable self-electric powered sewing machine, comprising a light, small housing 12 of generally solid elliptical shape, comprising an elongated body 14 and a head portion 16 having a narrow transverse fabric receiving slot 18 therein. I provide a novel type of stitch forming means mounted in said head 16 above and below said slot, specifically a needle reciprocating mechanism 20 mounted in the upper head portion 22 and a fabric feeding mechanism 24 and thread looping mechanism 26 contained in the lower head portion 28.

I provide a thread supply such as the spool 30 mounted in the spool holding compartment 32

and suitable means to feed thread 34 forward from said spool 30 to the hole 36 in the needle 38 under tension.

My self-contained unit has an electric motor 40 mounted therein, preferably near the rear end thereof, and a flexible electric cord 42, preferably projecting out the rear end of said body portion 14, connecting said motor 40 to an external source of electric supply and I provide in the motor circuit an externally operated switch 44 for said motor in said housing 12 and I provide suitable power transmitting means 46, including gear means operated by said electric motor for actuating the stitch forming means.

15 All parts within the housing 12, with the exception of the motor and transmission elements, may be made out of suitable plastic material, wood, metal or any other suitable material, but are preferably made out of a cast plastic to provide a minimum amount of weight and the ready prefabrication of the various parts.

As stated, the housing 12 is preferably light and so small that it may be grasped within the palm of the hand and is of generally cylindrical 25 shape, preferably modified into a so called teardrop form, namely, with an enlarged head portion 16 of generally partially spherical shape, having said transverse fabric receiving horizontal slot 18 therein and the elongated body 14 for 30 facile grasping in the palm of the hand 48 of the user. As shown in Fig. 2, said body portion tapers to a small rear end 50, having a central hole 52 therein providing a cord receiving hole. Said housing also has the switch button hole 54 35 preferably in the top thereof as shown. For initial assembly, the body portion 12 is preferably constructed in two readily moldable vertically centrally split portions 14a and 14b suitably secured together by screws or cement, or in any 40 other suitable manner. Said body portion is shaped to provide from rear to front an electric motor holding compartment 56 and a central spool holding compartment 32 preferably extending inwardly from one side wall thereof, as 45 shown in the near half 14b. Said compartment 32 has an inner wall 58 at a spaced distance from the opposite housing wall 60 in the vertical half 14a as shown in Fig. 6.

Said body portion 14 is provided with the 50 closed front end 62 preferably having a centrally cut away upper portion 64, the thread guide hole 66 and the central transmission shaft bearing hole 68. The spool holding compartment 32 may be provided with the partially cylindrical cover 70 pivotally mounted on the pivot pin 72 on the rear end thereof, provided with the spring 74 normally urging said cover 70 to a closed position. The spool compartment 32 is 55 preferably of a size to just contain the spool 30 to permit it to revolve freely therein to supply the thread 34 as required in use.

Said head 20 comprises the upper generally 60 semispherical head portion 22 pivotally mounted on a pivot pin 76 extending across the upper end of the center open portion 64 of said front wall 62 and mounted in bearings on the upper end of said front wall each side of said open portion 64. Said upper head portion has a lug portion 78 projecting rearwardly therefrom, for a 65 purpose to be described and has a generally hollow interior having a vertical guide portion or web 80 projecting downwardly adjacent the front end thereof centrally slotted as at 82, with the walls of each slot having channel providing lips 75 84 on each side of each edge thereof for reciproca-

tion of a needle plate 86 thereon in a manner to be described, and a bearing portion 88 projecting downwardly therefrom, having an axial shaft bearing hole 90 therein and a rear wall 92 having a central cut away portion 94 adjacent the lower edge thereof to permit pivoting of said head portion over the central transmitting pinion gear 96.

The lower complementary semispherical head portion 28 in the embodiment shown is permanently mounted on the lower portion of said body portion front wall 62 by screws, cement or in any other suitable manner and also has a generally hollow interior having the bearing portion 98 projecting upwardly therefrom, having the axial shaft bearing hole 100 therein and the rear wall 102 having the central open portion 104 therein and a top wall 106, in the embodiment shown having a narrow rear portion 108 on which said pivoted upper head portion 22 may rest, having the central transverse pinion gear receiving slot 110 therein and the downset front portion 112 providing, with the lower wall 114 of said top portion, the transverse fabric receiving slot 18 of said head, having a transverse fabric feeding means slot 116 therein. While I have shown the slot 48 provided by the downset portion 112 of the top wall 106 of said lower head portion, it is obvious that said fabric receiving slot may be provided entirely in said upper head portion or partially between said upper and lower head portions.

I will now describe generally how the parts of my improved mechanism are mounted in the various compartments of the housing. As stated, the electric motor 40 is provided in the electric motor holding compartment 56. While any suitable type of a small horsepower electric motor may be provided, I have shown in the drawings a suitable type for this purpose. The motor comprises the U-shaped stator 118, having the U base 120 and spaced U arms 122 projecting forwardly therefrom. The U base has the magnetizing coil 124 wrapped around it to provide a magnetic field between the forwardly projecting arms 122 thereof. Suitable rotor supporting plates 126 are joined to opposite sides of said U arms 122 and are provided with suitable bearing holes 128 therein for mounting the bearing shaft 130 of the rotor 132 thereon. The far side of the rotor shaft 130 is provided with the power transmitting bevel gear 134 thereon. The opposite end of said shaft 130 is flattened as at 136 on diametrically opposite sides thereof.

Said motor is provided with a double blade or pole, make and break timing mechanism actuated by said rotor shaft. For this purpose a supplemental insulating plate 138 joins the near sides of said U arms 122 adjacent the coil 120 and has fixedly mounted thereon the spring blades 140 which project forwardly on each side of said flattened end 136 of said rotor shaft 130 and terminate forwardly thereof in the inwardly projecting contacts 142. It is thus obvious that on each revolution of the rotor shaft 130, the contacts 142 are in contact with each other twice, as the flat portions 136 are contained between the spring blades 140, but that said contacts 142 are also broken twice during each revolution of the shaft, thus creating the cycle of magnetic force, as the elongated portions 144 between said flattened portions 136 also spread the spring blades 140 twice during each revolution of said shaft 130.

The make and break operating switch 44 com-

prises the resilient fixed blade 146 rigidly mounted in said body 14 in the rear end of said switch button slot 54 to project forwardly therefrom underneath said switch button slot 54 and terminates in a front end 148 projecting first upwardly and then forwardly and has the contact 150 on the upper surface thereof just prior to said upward bend. The normally movable resilient blade 152 is also mounted in said body portion 10 adjacent the rear end of said switch button slot 54 above said fixed blade 146 to project forwardly within said slot 54 and has the switch button or handle 156 mounted on the upper surface thereof to project outwardly through said slot 54. With this construction, it is obvious that when the switch button 156 is pressed inwardly, the movable blade 152 will be urged downwardly to abut the contact 150 of said resilient fixed blade 146 to complete the circuit through said switch, but that when said upper head portion 22 is pivoted to an open position, the rearwardly projecting lug 78 thereof will strike the forward projection 148 of said resilient fixed blade 146 to urge it downwardly so that depression of the switch button 156 will not depress the movable blade 152 far enough downwardly to make contact with the depressed fixed blade 146, so that it will be impossible to close the switch on manipulation of the button 156 while the pivoted head portion 22 is open.

I provide the two wire cable 42 with a male element 158 of an electric terminal adapted to be plugged in to the female element thereof permanently mounted on the wall of the building.

35 Said cable 42 extends through the hole 52 in the rear end of said body 14 and has one terminal 160 thereof connected to one end of said coil 124 and the other terminal 162 thereof connected to said movable switch blade 152. A wire 164 connects 40 the opposite coil terminal to one blade 140 of said make and break timing mechanism and the wire 166 connects the other blade 140 of said make and break timing mechanism to the fixed blade 146 of said make and break switch 44.

45 As stated, one feature of my invention relates to the novel type of means I employ for transmitting power forwardly to the stitch forming mechanism hitherto described, which, in my preferred embodiment, comprises rigid positive gearing.

50 As stated, I provide the large bevel gear 134 mounted on the end of said motor rotor shaft 130 at the opposite side of said housing from said spool holding compartment 32. As gearing to transmit the motion of said motor forwardly, I provide the relatively large bevel gear 168 preferably of greater diameter than the length of said spool holding compartment 32, having the shaft 170 mounted in suitable bearings 172 on the inner wall 58 of said spool holding compartment 32 and opposite housing wall 60, in mesh with said bevel gear 134.

65 I provide a suitable transmission shaft 174 extending through the bearing hole 68 in the front wall 62 of said body portion 14 having an enlarged bevel gear 176 on the rear end thereof in mesh with said axially extending bevel gear 168 and a common pinion drive gear 96 on the front end thereof within said head portion.

70 As my novel type of mechanism to reciprocate the needle 38, I provide the needle moving drive plate 86 vertically reciprocally mounted in the channels 85 provided by the lips 84 on the inner walls of the guide portion 80 adjacent the central slot 82 therein to reciprocate vertically in said channels, and I provide said drive plate with the

horizontal slot 178 at a closely spaced distance from the lower end thereof, said plate 86 being also provided with suitable needle holding means, in the embodiment shown comprising the radially slotted externally threaded hollow needle holding projection 180 projecting downwardly centrally thereof, and I provide the externally threaded knurled nut 182 threadedly mounted thereon to clamp it around the upper end of a needle 38 contained within the hollow interior thereof for securing the upper end of said needle within said slotted projection. I provide a needle drive shaft 184 mounted in the axial bearing hole 90 in said upper head projection 88, having a driven pinion gear 186 mounted on the rear end thereof in mesh with said common drive pinion 96 and a front end first bent radially outwardly as at 188, and then having a tip 190 bent forwardly to move laterally within said slot 178 in said reciprocating needle holding drive plate 86 to provide an eccentric actuating pin to vertically reciprocate said needle plate 86 and contained needle 38 on each revolution of said drive shaft. As stated, this portion of my stitch forming means is mounted in said upper head portion 22.

As stated, the fabric feeding mechanism and stitch looping mechanism are located in said lower head portion 28. For this purpose, I provide a fabric feeder having a plate 192 at the upper end thereof, having its upper edge serrated as at 194 in a manner to provide flat toothed edges facing towards the desired direction of travel of the fabric. Said fabric feeding plate 192 is provided with the elongated slot 196 for receiving the end of a needle 38 therein while being reciprocated. Said plate 192 is provided with the leg 198 projecting downwardly centrally thereof, having a bearing hole 200 centrally thereof and a vertical pivot pin receiving slot 202 adjacent the lower end thereof. The drive shaft 204 is provided for the lower head portion 28 mounted in said axial bearing hole 100 in said lower head bearing projection 98, having a driven pinion gear 206 mounted on the rear end thereof in mesh with said central common drive gear 96 and a front end bent first radially outwardly as at 208 and then forwardly terminating in the tip 210 projecting through said fabric feeding leg hole 200 to provide an eccentric pin 210 for rotating said fabric feeding plate 192.

To restrain the lower end of said lug, I provide the pivot pin, in the embodiment shown comprising the screw 212 projecting laterally forwardly from said lower portion and extending through said vertical leg slot 202. It is thus obvious that said feeding plate 192 and leg 198, pin 210 and pivot pin 212, form the fabric feeding means for rotation of the plate 192 forwardly in its slot at the desired portion of each cycle of revolution of the master transmission drive gear 96.

The thread looping mechanism 26 comprises the looper 214 having diametric arms 216 and 218, having edges curved to loop the thread at the desired portion of each stitch forming cycle, rigidly mounted on the front end of said eccentric pin portion 210 to be revolvable therewith. Said looping mechanism is of standard shape and one of said arms 218 thereof may have the projecting tips 220 and 222 for the usual thread looping purposes. It is thus obvious that both the fabric feeding mechanism 24, as explained, and the thread looping mechanism 26 perform their functions through the medium of the common drive pin 210 rotated by the common drive shaft 204

75 and common gear 206 from the master drive pinion 96.

If desired, a spring 226 may be rigidly mounted on the lower edge of said guide portion 80 and provided with a downwardly curved portion 228, having a needle receiving hole 230 therein to urge the fabric 232 downwardly against the serrated upper surface 194 of the fabric feeding plate 192.

I also provide a novel type of device for urging the needle sharply upwardly from the fabric, in the embodiment shown comprising a flat spring 234 secured to the opposite end of the lower edge of said guide portion 80, having an inwardly projecting end 236, having a needle receiving hole 238 therein adapted to be bent downwardly by said nut 182 as it is urged downwardly on reciprocation of the needle, to urge said nut 182 and attached needle 38 sharply upwardly away from said fabric when said nut 182 is no longer urged downwardly by the tip 190.

I also provide a thread tension device, in the embodiment shown and as shown in Figs. 2 and 3, comprising the two relatively movable discs 240 and 242 having suitable holes for mounting on the threaded screw 244, normally urged against each other by the spring 246 interposed between the outermost disc and the head 248 of said screw 244, which fits into a suitable hole 245, in the embodiment shown in the front wall 62 of said head. It is obvious, however, that any other suitable type of thread tensioning device may be employed.

When first used, the thread 34 is threaded 35 through the thread hole 66, in between the discs 240 and 242 and through the hole 36 in the needle 38, with the spool 39 being loosely mounted in said spool holding compartment 32, with the upper head portion 22 being suitably raised for this purpose. During this operation, any depression of 40 the switch button 156 will not permit the motor to start, due to the fact that the projection 18 moves the fixed contact blade 146 out of position for any contact of the movable blade 152 therewith.

When, however, the upper head portion 22 is closed so that it may be latched in position by the male snap fastener projections 252, projecting upwardly from the rear end 103 of said upper wall portion 106 of said lower head portion 28, fitting 50 into suitable female sockets 250 on the lower edge of said upper head portion 22, then the device is safe to operate and may be grasped in the palm of the hand 48 and brought adjacent the fabric 55 232 as shown in Fig. 1.

Fig. 1 illustrates a hem 254 being formed in the fabric. The edge of the fabric is first looped over to provide the lapped portion 256 which is then inserted transversely in the slot 18 in the head of 60 my improved sewing machine, the switch button 156 is depressed, causing the motor to operate, causing the stitch forming mechanisms to operate in the manner explained and the fabric 232 acted upon may be held in the opposite hand 65 while the first hand 48 guides the sewing machine 49 relative to the fabric, the machine itself operating to feed the fabric transversely through the transverse slot 18. It is obvious that the invention may be operated with complete safety as long 70 as the upper head portion 22 is closed and the device may be used in almost any position. When the stitch 258 is completed, the thread may be cut as usual and the sewing machine is ready for another job. It need not be rethreaded until it is desired to insert a new source of thread sup-

ply or spool 30 within the spool holding compartment 32.

It is apparent that I have provided a novel type of sewing machine with the advantages described above.

It is understood that my invention is not limited to the specific embodiment shown and that various deviations may be made therefrom without departing from the spirit and scope of the appended claims.

What I claim is:

1. An electric sewing machine for hand operation, comprising a hollow housing having an elongated body section and a head section, said head section having an upper portion and a lower portion, said upper and lower portions being vertically spaced from each other to provide a fabric receiving slot, needle reciprocating mechanism in the upper portion including a drive shaft, thread looping mechanism in the lower portion including a drive shaft parallel to the needle reciprocating mechanism drive shaft, fabric feeding mechanism keyed on the thread looping drive shaft and extending into said slot, means in said body for supplying thread to said needle, an electric motor in said body, an electric circuit connection for activation of said motor from an external power source, and gearing operatively connecting said motor to the drive shafts of the needle reciprocating and thread looping mechanisms.

2. An electric sewing machine for hand operation, comprising a hollow housing having an elongated body section and a head section, said head section having an upper portion and a lower portion, said upper and lower portions being vertically spaced from each other to provide a fabric receiving slot, needle reciprocating mechanism in the upper portion including a drive shaft, means for detachably mounting a needle therein, thread looping mechanism in the lower portion including a drive shaft parallel to the needle reciprocating mechanism drive shaft, fabric feeding mechanism, means for reciprocating the fabric feeding mechanism mounted on the thread looping drive shaft and extending into said slot, means in said body for supplying thread to said needle, an electric motor in said body, an electric circuit connection for activation of said motor from an external power source, and gearing operatively connecting said motor to the drive shafts of the needle reciprocating and thread looping mechanisms.

3. An electric sewing machine for hand operation, comprising a hollow housing having an elongated body section and a head section, said head section having an upper portion and a lower portion, said upper and lower portions being vertically spaced from each other to provide a fabric receiving slot, needle reciprocating mechanism in the upper portion including a drive shaft, thread looping mechanism in the lower portion including a drive shaft parallel to the needle reciprocating mechanism drive shaft, fabric feeding mechanism keyed on the thread looping drive shaft and extending into said slot, means in said body for supplying thread to said needle, an electric motor in said body, an electric circuit connection for activation of said motor from an external power source, gearing operatively connecting said motor to the drive shafts of the needle reciprocating and thread looping mechanisms, and manually movable switch means on the body for opening and closing said electric circuit.

4. An electric sewing machine for hand operation, comprising a hollow housing having an

elongated body section and a head section, said head section having an upper portion and a lower portion, said upper and lower portions being vertically spaced from each other to provide a fabric receiving slot, needle reciprocating mechanism in the upper portion including a drive shaft, means for detachably mounting a needle therein, thread looping mechanism in the lower portion including a drive shaft parallel to the needle reciprocating mechanism drive shaft, fabric feeding mechanism, means for reciprocating the fabric feeding mechanism mounted on the thread looping drive shaft and extending into said slot, means in said body for supplying thread to said needle, an electric motor in said body, an electric circuit connection for activation of said motor from an external power source, gearing operatively connecting said motor to the drive shafts of the needle reciprocating and thread looping mechanisms, and manually movable switch means on said body for opening and closing the electric circuit.

5. An electric sewing machine for hand operation, comprising a hollow housing having an elongated body section and a head section, said head section having an upper portion and a lower portion, said upper and lower portions being vertically spaced from each other to provide a fabric receiving slot, needle reciprocating mechanism in the upper portion including a drive shaft, thread looping mechanism in the lower portion including a drive shaft parallel to the needle reciprocating mechanism drive shaft, fabric feeding mechanism keyed on the thread looping drive shaft and extending into said slot, means in said body for supplying thread to said needle, an electric motor in said body, an electric circuit connection for activation of said motor from an external power source, gearing operatively connecting said motor to the drive shafts of the needle reciprocating and thread looping mechanisms, manually movable switch means on said body for opening and closing the electric circuit, and spring means normally urging said switch means to circuit open position.

6. An electric sewing machine for hand operating, comprising a hollow housing having an elongated body section and a head section, said head section having an upper portion and a lower portion, said upper and lower portions being vertically spaced from each other to provide a fabric receiving slot, needle reciprocating mechanism in the upper portion including a drive shaft, means for detachably mounting a needle therein, thread looping mechanism in the lower portion including a drive shaft parallel to the needle reciprocating mechanism drive shaft, fabric feeding mechanism, means for reciprocating the fabric feeding mechanism mounted on the thread looping drive shaft and extending into said slot, means in said body for supplying thread to said needle, an electric motor in said body, an electric circuit connection for activation of said motor from an external power source, gearing operatively connecting said motor to the drive shafts of the needle reciprocating and thread looping mechanisms, manually movable switch means on said body for opening and closing said electric circuit, and spring means normally urging said switch means to circuit opening position.

7. An electric sewing machine for hand operation, comprising a hollow housing having an elongated body section and a head section, said head section having an upper portion and a lower portion, said upper and lower portions being verti-

11

cally spaced from each other to provide a fabric receiving slot, needle reciprocating mechanism in the upper portion including a drive shaft and a driven pinion gear mounted on said drive shaft, thread looping mechanism in the lower portion including a drive shaft parallel to the needle reciprocating mechanism drive shaft and a driven pinion gear mounted on said drive shaft, fabric feeding mechanism keyed on the thread looping drive shaft and extending into said slot, means in said body for supplying thread to said needle, an electric motor in said body, an electric circuit connection for activation of said motor from an external power source, and gearing operatively connecting said motor to the pinion gears of the needle reciprocating and thread looping mechanisms.

8. An electric sewing machine for hand operation, comprising a hollow housing having an elongated body section and a head section, said head section having an upper portion and a lower portion, said upper portion being pivotally mounted on said body for movement to open and to closed position with respect to the lower portion; said upper and lower portions being vertically spaced from each other when the upper portion is pivotally mounted in closed position to provide a fabric receiving slot, needle reciprocating mechanism in the upper portion including a drive shaft and a driven pinion gear mounted on said drive shaft, thread looping mechanism in the lower portion including a drive shaft parallel to the needle reciprocating mechanism drive shaft and a driven pinion gear mounted on said drive shaft, fabric feeding mechanism keyed on the thread looping drive shaft and extending into said slot, means in said body for supplying thread to said needle, an electric motor in said body, an electric circuit connection for activation of said motor from an external power source, gearing operatively connecting said motor to the pinion gears of the needle reciprocating and thread looping mechanisms when the upper portion is in closed position.

12

9. An electric sewing machine for hand operation, comprising a hollow housing having an elongated body section and a head section, said head section having an upper portion and a lower portion, said upper portion being pivotally mounted on said body for movement to open and to closed position with respect to the lower portion, said upper and lower portions being vertically spaced from each other when the upper portion is pivotally mounted in closed position to provide a fabric receiving slot, needle reciprocating mechanism in the upper portion including a drive shaft and a driven pinion gear mounted on said drive shaft, fabric feeding mechanism keyed on the thread looping drive shaft and extending into said slot, means in said body for supplying thread to said needle, an electric motor in said body, an electric circuit connection for activation of said motor from an external power source, and gearing operatively connecting said motor to the pinion gears of the needle reciprocating and thread looping mechanisms when the upper portion is in closed position, and manually movable switch means on said body for opening and closing said circuit, said switch means being inoperative when said upper portion is in open position.

HARRY W. HUNTINGTON.
